PLAYING CARD HOLDER AND DISPENSER

James T. Russell, 19460 Cranbrook Drive, Detroit, Mich.

Filed Dec. 28, 1962, Ser. No. 72,974

Term of patent 14 years

(Cl. D34—13)

FIG. 1 is a view in perspective of a playing card holder and dispenser embodying my new design;

FIG. 2 is a top plan view;

FIG. 3 is a side elevational view;

FIG. 4 is a rear elevational view; and

FIG. 5 is a front elevational view.

I claim:

The ornamental design of a playing card holder and dispenser, substantially as shown.
